UNITED STATES PATENT OFFICE.

HOWARD M. DUDLEY, OF PHILADELPHIA, PENNSYLVANIA.

DYEING-MACHINE.

1,280,186.

Specification of Letters Patent.

Patented Oct. 1, 1918.

Application filed June 1, 1917. Serial No. 172,171.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention refers to dyeing machines and refers particularly to a machine suitable for the dyeing of worsted top and warp balls.

One object of my invention is a device whereby worsted top, warp balls and similar fibers may be thoroughly and evenly dyed and treated with liquids and air.

Another object of my invention is a device whereby fibers in the condition stated above may be dyed and treated without injury to the fiber.

Another object of my invention is a device whereby fibers in the condition stated above may be readily and rapidly packed into dyeing chambers and compressed into a form suitable for even penetration.

Another object of my invention is a device whereby a considerable number of balls, tops &c. may be dyed equally.

These and other objects of my invention will be evident upon a consideration of my specification and claims.

The dyeing of worsted tops, warp balls and similar fibers presents several difficulties which must be overcome in order to produce even and satisfactory results.

On account of the physical condition of the fibers they must not be disturbed during the dyeing operation, but must be retained in their original condition.

I have overcome all of these difficulties and the device of my invention will dye fiber forms of this character evenly and completely.

In the accompanying drawings, illustrating several modifications of the device of my invention, similar parts are designated by similar numerals.

Figure 1 is a side view partly broken away in cross-section to disclose the various members.

Fig. 2 is a cross-section through the line 2—2 of Fig. 1.

Fig. 3 is a cross-section through the line 3—3 of Fig. 1.

Fig. 4 is a top-plan view of a modified form of my device, with parts removed.

Fig. 5 is a top-plan view of a portion of a foraminous plate.

Fig. 6 is a developed side elevation of a portion of the foraminous plate of Fig. 5. 60

Fig. 7 is a cross-section through the line 7—7 of Fig. 5.

Fig. 8 is a broken vertical-section illustrating the valve on the pipe leading to the testing device. 65

Fig. 9 is a front view looking in the direction of the arrow 9 of Fig. 8, partly in section.

Fig. 10 is a cross-section through the line 10—10 of Fig. 8. 70

Fig. 11 is a top plan view of the member abuttable upon the upper foraminous plates within the fiber chambers.

The device comprises a receptacle formed of the cylindrical member 10, attached to the conical member 11 by means of the bolts 12, 12 and the conical member 11 is attached to the pump chamber 13 of the pump 14 by means of the bolts 15, 15. The top portion of the receptacle has an overflow pipe 16, discharging into the liquor tank 17. The lower portion of the tank 17 is connected to a pipe 18 having the valve 19, the pipe 18 being connected to the pump delivery pipe 21. The pipe 21 is connected to the pipe 22 having a valve 23. The pipe 22 is connected with pipe 24 having the valve 25. The pipe 22 is connected with a dye dissolving tank not shown, and the pipe 24 is connected with a source of fresh water supply. The pump 90 chamber 13 carries the pipe 26 with the valve 27. 85

Within the cylindrical member 10 of the receptacle is fixedly positioned a series of cylindrical fiber containers each comprised of the imperforate side 28 and the foraminous bottom 29. Adjacent to each fiber container are ports 30, 30^A, the port 30 having the valve 32. Situated slidably within each fiber container is a foraminous top 37 and 95 slidable within the fiber container and capable of abutment upon the top 37 is the annular member 38 with its extended ring portion 39. By means of the wing screw bolts 40, 40 which extend through the ring 39 and thread into holes in the extended portion 41 of the cylindrical member 10, the member 38 may be fixed in any predetermined position within the receptacle. 100

The foraminous top 37 and the foraminous bottom 29 are of the same construction and consist of a series of parallel and inter-

secting bars 31, 31, carrying upwardly 44, 44 and downwardly 45, 45 extended pointed members.

Within the conical member 11 is an imperforate conical member 42, supported by the supporting bars 43, 43. The conical member 11 abuts upon the imperforate cylindrical member 46 in the receptacle 10.

The construction of the valve 32 and the means for inserting the testing device 59 are shown in Figs. 8, 9 and 10.

The stem 52 has the one-way port 53, the pin 54 is inserted within the groove 55 to prevent the withdrawal of the valve stem 52, and the stop-pin 56 sets the valve for the free passage of liquid through the port 30 or for the complete stoppage of said passage.

Within the wall of each cylinder is a chamber 57, into which the ports 30 and 30^A lead, said chamber being threaded upon its inner surface. A threaded cap 58 capable of enmeshment with the threads of the chamber 57 is slidably movable over the testing device 59. In order to insert the testing device 59, the two caps 58, 58 are slid inwardly upon the testing device, the testing device inserted between the two openings of the ports 30, 30^A and the two caps 58, 58 threaded with the threads of the chamber 57 and screwed inwardly until a tight joint is effected by means of the gasket 60.

A perforated steam pipe 61 is inserted below the foraminous bottom 29.

In the modification shown in Figs. 4 and 5 the receptacle 10 is rectangular, and the member 11 is of pyramidal form to fit therewith.

The operation of the device is as follows: The member 38 and the foraminous top 37 are removed and the warp balls 62, 62 inserted into the fiber container, the foraminous top 37 is then placed upon the upper warp ball, the member 38 inserted within the fiber container and the top 37 pressed downwardly, by means of the member 38 operated through the wing screw bolts 40, 40, thus compressing the warp balls into the desired condition. The pump 14 is started and a dye solution allowed to enter the pump 14 through the pipe 22, 21, the valves 19, 25 and 27 being closed. When the proper amount of dye liquor has been introduced, the valve 23 is closed and the valve 19 opened. The liquor now passes from the tank 17 into the pump 14 and is forced upwardly around the conical member 42 through the space immediately above where it is maintained at a proper temperature by the steam pipe 61, and then upwardly through the foraminous bottom 29, the warp balls 62, 62, the foraminous top 37 and then through the overflow pipe 16 back into the tank 17. A portion of the liquid also passes upwardly through the port 30 into the testing device 59, containing fiber, and from thence outwardly

into the receptacle and back into the tank 17 through the overflow pipe 16. By closing the valve 32 the condition of the fiber may be determined by examining that within the testing device 59 without interrupting the operation in the larger device.

When the dyeing operation is completed the valve 19 is closed and the valve 27 is opened, thus draining all of the liquid from the device through the pipe 26. Valve 27 is then closed and valve 25 opened, and fresh water for washing purposes is delivered to the pump 14 through the pipes 24, 21 and forced upwardly through the device. After proper washing the valve 25 is closed and valve 27 opened, draining the water from the receptacle. If it is desirous of treating the fiber with air, for oxidizing, drying or other purposes, the pump 14 is stopped and air forced through the pipe 26, the receptacle, and the fiber contained therein.

I do not limit myself to the particular size, shape, number or arrangement of parts as described and shown, all of which may be varied without going beyond the scope of my invention as described and claimed.

What is claimed is:

1. In a dying machine, in combination, a fiber chamber, a liquid chamber below the fiber chamber, a testing device exterior of the fiber chamber, a conduit within the wall of the fiber chamber connecting the liquid chamber with the testing device, a valve in said conduit, a second conduit connecting the testing device with a means for returning the liquid to the liquid chamber, means for removing the testing device from engagement with the two conduits, and means for the continuous circulation of a liquid through the conduits and the testing device. 105

2. In a dyeing machine, in combination, a receptacle, a series of fiber chambers having imperforate sides within the receptacle, each chamber having a fixed foraminous bottom and a foraminous top slidably movable within the chamber, means for moving the tops with respect to the bottoms and for retaining the tops in any predetermined positions, a liquid space below the fiber chambers, a series of testing devices exterior of the receptacle, a conduit within the wall of each fiber chamber connecting a testing device with the liquid chamber, means for removing the testing devices from the conduits without interrupting the dyeing operation, 115 means for passing a liquid through the chambers and the testing devices and means for causing a continuous circulation of a liquid through the chambers and the testing devices. 120

3. In a dyeing machine, in combination, a receptacle, a series of fiber chambers having imperforate sides within the receptacle, each chamber having a fixed foraminous bottom and a foraminous top slidably movable 130

- within the chamber, means for moving the tops with respect to the bottoms and for retaining the tops in any predetermined positions, a liquid space below the fiber chambers, a series of testing devices exterior of the receptacle, a conduit within the wall of each fiber chamber connecting a testing device with the liquid chamber, a conduit connecting each testing device with the upper 10 part of the receptacle, a valve in each conduit between the liquid chamber and a testing device, means for continuously passing a liquid through the fiber chambers and the testing devices, means for heating the liquid 15 within the receptacle and means for withdrawing the liquid from the receptacle.
4. In a dyeing machine, in combination, a receptacle, a series of fiber chambers having imperforate sides within the receptacle, 20 each chamber having a fixed foraminous bottom and a foraminous top slidably movable within the chamber, means for moving the tops with respect to the bottoms and for retaining the tops in any predetermined positions, a liquid space below the fiber chambers, a series of testing devices exterior of the receptacle, a conduit within the wall of each fiber chamber connecting a testing device with the liquid chamber, a conduit connecting each testing device with the upper 25 part of the receptacle, a valve in each conduit between the liquid chamber and a testing device, a second liquid chamber having an upwardly divergent imperforate member below the first mentioned liquid chamber, a pump, means whereby the pump will force a liquid through the second liquid chamber, 30 the first liquid chamber, the series of fiber chambers and the testing devices, means for returning to the pump all the liquid that has passed through the fiber chambers and the testing devices, means for heating the 35 liquid and means for withdrawing from the device all the liquid that has not passed through the fiber chambers.
5. In a dyeing machine, in combination, a receptacle, a series of fiber chambers having imperforate sides within the receptacle, each chamber having a fixed foraminous bottom 40 with upwardly extended members, and a movable foraminous top with downwardly extended members, means for compressing a fiber within the chambers by the downward movement of the tops, an imperforate member around which the fiber chambers are situated, a liquid chamber below the series of fiber chambers, a series of testing devices exterior of the fiber chambers, a conduit within the wall of each fiber chamber 45 connecting the liquid chamber with a removable testing device, a conduit connecting each testing device with the upper part of the receptacle, a valve in each conduit between the liquid chamber and a testing device, a second liquid chamber having an upwardly divergent imperforate member below the first mentioned liquid chamber, a pump, means whereby the pump will force a liquid through the second liquid chamber, 50 the first liquid chamber, the series of fiber chambers and the testing devices, means for returning to the pump all the liquid that has passed through the fiber chambers and the testing devices, means for heating the 55 liquid and means for withdrawing from the device all the liquid that has not passed through the fiber chambers.

Signed at New York, in the county of New York and State of New York, this 17th 75 day of May, 1917.

HOWARD M. DUDLEY.
